The Copenhagen Buckle, publish date unknown, retrieved from internet (Feb. 12, 2025). <URL: <https://copenhagentrade.dk/products/baby-accessory/harness-safety-products/the-copenhagen-buckle/>> (Year: 2025) (Year: 2025).*

Primary Examiner — Joseph Kukella
Assistant Examiner — Heather Wencel

(57) **CLAIM**

The ornamental design for a safety buckle as shown and described.

DESCRIPTION

1. Safety buckle

1.1 : Perspective

1.2 : Exploded

1.3 : Front

1.4 : Back

1.5 : Right

1.6 : Left

1.7 : Top

1.8 : Bottom

The design shows a new safety buckle; the features shown in broken lines in the drawings depict environmental subject matter only, and form no part of the claimed design.
